UNITED STATES PATENT OFFICE.

EMMA R. LEE THAYER AND ELIZABETH H. CASSARD, OF NEW YORK, N. Y.

DESIGN FOR A FOLDING PLAYHOUSE.

43,949.

Specification for Design.

Patented Apr. 29, 1913

Application filed November 29, 1912. Serial No. 734,208. Term of patent 14 years.

To all whom it may concern:

Be it known that we, EMMA R. LEE THAYER and ELIZABETH H. CASSARD, citizens of the United States, residing in the city of New York, borough of Manhattan, in the county and State of New York, have invented a new, original, and ornamental Design for a Folding Playhouse, of which the following is a specification, reference being had to the accompanying drawing, forming part thereof.

The figure is a perspective view of a play house, showing our new design.

We claim:

The ornamental design for a folding play house, as shown.

EMMA R. LEE THAYER.
ELIZABETH H. CASSARD.

Witnesses:

HENRY W. THAYER,
M. P. SEVERANCE.
